UNITED STATES PATENT OFFICE

151,160

DESIGN FOR A FRUIT HOLDER

Milo J. Manca, Seattle, Wash.

Application June 6, 1946, Serial No. 130,469

Term of patent 7 years

(Cl. D44—29)

To all whom it may concern:

Be it known that Milo J. Manca, a citizen of the United States, residing at Seattle, King County, Washington, has invented a new, original, and ornamental Design for a Fruit Holder, of which the following is a specification, reference being had to the accompanying drawing, forming a part hereof, in which

I claim:

The ornamental design for a fruit holder, substantially as shown.

MILO J. MANCA.
